Des. 240,716
Patented July 27, 1976

240,716

COMBINED CLOSURE CAP AND POURING SPOUT

Robert Hegi, im Buehl, CH 8113 Boppelsen, Switzerland

Filed Sept. 16, 1974, Ser. No. 505,991

Term of patent 14 years

Int. Cl. D9—07

U.S. Cl. D9—278

Fig.1

Fig.2

Fig.3

Fig.4

Fig.5

Fig.6

FIG. 1 is a front elevational view of a combined closure cap and pouring spout showing my new design;

FIG. 2 is a vertical sectional view thereof;

FIG. 3 is a top plan view;

FIG. 4 is a bottom plan view;

FIG. 5 is an elevational view showing a modified form of my new design; and

FIG. 6 is an elevational view showing another modified form of my new design.

The top views of the modifications of FIGS. 5 and 6 are the same as FIG. 1.

I claim:

The ornamental design for a combined closure cap and pouring spout, as shown and described.
